WATER SOFTENING SYSTEM

Lawrence E. Albertson, Minneapolis, Minn., assignor to The McKays Company, St. Paul, Minn., a corporation of Delaware

Application March 10, 1947, Serial No. 733,483

4 Claims. (Cl. 210—24)

1

This invention relates to a water softening system and apparatus, and has more particular relation to a so-called "rental" water softener.

An object of the invention is to provide a water softening system and apparatus which will be an improvement generally over the disclosure of U. S. Letters Patent No. 2,329,350, to Theodore Kaysen, Jr., for Water Softening System and Apparatus, granted September 14, 1943.

A further object is to provide a water softening system and apparatus wherein will be incorporated desirable and improved features and characteristics of construction novel both as individual entities of the water softening system and apparatus and in combination with each other.

And a further object is to provide a so-called "rental" water softener constituted as herein-after set forth.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification,

Fig. 1 is an elevational view of a water softener including the features and characteristics of the invention, as when in water softening operation;

Fig. 2 is an elevational view, partially in section and partially broken away, of the water softener of Fig. 1, as when a mineral bed of zeolite of said water softener is connected up for regeneration;

Fig. 3 is a detail sectional view of a fitting with valve of said water softener, disclosing said valve in closed position;

Fig. 4 is a view corresponding generally with the disclosure of Fig. 3, but showing the valve situated to permit restricted flow;

Fig. 5 is a view corresponding generally with the disclosures of Figs. 3 and 4, but showing the valve in open position;

Fig. 6 is a sectional view detailing entities or elements of the water softening system and apparatus at positions in which they are situated when brine solution is being washed or removed from the mineral bed of zeolite;

Fig. 7 is a sectional view, taken on line 7—7 in Fig. 6;

Fig. 8 is a sectional view, taken on line 8—8 in Fig. 6; and

2

Fig. 9 is an elevational view of a time operated controlling means for a latching device of the water softener;

With respect to the drawings and the numerals of reference thereon, an inlet connection 15 leads from a source (not shown) of water supply by pipe connections 16, 17 and 17' to a water softening medium container 18, and by way of a pipe connection 19 to locations of use, such as faucets (not shown), for water. An outlet connection 20 from said water softening medium container leads by way of a pipe connection 26 to the pipe connection 19. A manually actuatable valve 21 in the pipe connection 19, between the pipe connection 16 and the pipe connection 26, is normally closed, and water to be softened enters at the upper portion of the container 18 and passes downwardly through a softening medium 22, usually zeolite, in the container, which absorbs such constituents as calcium and magnesium from and releases sodium to the water. When the softening medium or zeolite reaches its saturated state, it is regenerated, by flushing with a salt brine solution.

A gravel supporting bed 23 for the softening medium or zeolite 22 is situated in the base of the container 18, and a usual distributor 24 in said gravel supporting bed is in communication with the outlet connection 20. The distributor 24 includes ports 25. The supporting bed 23 may be gravel, screens, cork, charcoal, or other suitable filtering means.

A salt tank 27, useful to the accomplishment of regeneration of the softening medium or zeolite 22, is not a part of the water softener when in water softening operation, as will be clear from Fig. 1, but is associated or assembled with the water softening medium container 18, as disclosed in Fig. 2, when the mineral bed of zeolite of said water softener is to be regenerated.

A valve casing 28 is secured, as at 29, to the outlet connection 20, and said valve casing is secured, as at 30, to the pipe connection 26.

A valve seat 31 of the valve casing 28 is disposed in the lower portion of a chamber 32 of said valve casing 28 in surrounding relation to a port 33 open to the pipe connection 26, and the outlet connection 20 opens to said chamber 32 at the side of said valve seat 31 opposite said port 33.

A first hollow tubular element 34 of the valve casing 28, integral with said valve casing and disposed above the chamber 32 in the disclosed embodiment of the invention, is for connection, as at 35, with a drain pipe 36 for the water softener.

A valve seat 37, situated between the chamber 32 and the first hollow tubular element 34, is disposed in the upper portion of said chamber 32 in surrounding relation to a port 38 between

the chamber 32 and the interior of said first hollow tubular element 34. The valve seat 37 is in vertical alinement with and parallel relation to the valve seat 31 and is disposed at the side of the outlet connection 20 which is opposite said valve seat 31.

A double valve 39 situated within the chamber 32 is adapted to be reciprocated between the valve seats 31 and 37. A lower closure surface 40 of the double valve 39 is adapted to be seated against the valve seat 31 to shut off communication between the outlet connection 20 and the pipe connection 26, and an upper closure surface 41 of said double valve is adapted to be seated against the valve seat 37 to shut off communication between said outlet connection 20 and the first hollow tubular element 34. The construction and arrangement are such that when the lower closure surface 40 is against the valve seat 31, the upper closure surface 41 is in spaced relation to the valve seat 37, and when said upper closure surface 41 is against said valve seat 37, said lower closure surface 40 is in spaced relation to said valve seat 31.

A valve stem 42, rigid with the double valve 39, extends through the interior of the first hollow tubular element 34, as well as through the port 38 between the chamber 32 and said first hollow tubular element, and is slidably mounted, as at 43, in an intermediate portion of the valve casing 28. A packing gland 44 about the valve stem 42 is for an obvious purpose.

A second hollow tubular element 45 of the valve casing 28, above the first hollow tubular element 34, is in alined relation with the ports 33 and 38, and the upper or free end portion of the valve stem 42 projects into the lower portion of said second hollow tubular element 45. A compression coil spring 46 upon said valve stem 42, between a collar 47 rigid with the valve stem and the base 48 of the interior of said second hollow tubular element 45, exerts resilient tension adapted to normally retain the upper closure surface 41 of the double valve 39 against the valve seat 37, thus to cause the lower closure surface 40 of said double valve to be situated in spaced relation to the valve seat 31.

The water softener incorporates a construction and arrangement, including a time controlled latching device, for retaining the lower closure surface 40 of the double valve 39 against the valve seat 31, against the action of the compression coil spring 46, when this is intentional, thus to cause the upper closure surface 41 of said double valve to be situated in spaced relation to the valve seat 31.

A fitting 49, threadably connected, as at 50, to the end portion of the second hollow tubular element 45 spaced from the first hollow tubular element 34, includes a cylindrical guide way 51 in alined relation with the valve stem 42 which slidably and rotatably receives an actuator stem 52 for said valve stem 42. The outer end portion of the actuator stem 52 projects to position beyond the fitting 49 and a button on said outer end portion is designated 53. The inner end portion of said actuator stem 52 is situated within the second hollow tubular element 45 and a collar rigid with said inner end portion is denoted 54. A compression actuator spring 55, within said second hollow tubular element 45 between the collars 47 and 54, is of greater strength than the compression coil spring 46.

The fitting 49 also includes a hollowed out portion in contiguous relation to the cylindrical

guide way 51 providing spaced apart bearings 56, 56 for trunnions 57, 57 of a rotatable latch element 58. Said rotatable latch element 58 is cut away at location between the trunnions 57, 57 to provide a latch edge 59 adapted to be releasably situated in an external thread 60 upon the actuator stem 52. The construction and arrangement will be such that the latch edge 59 has slant to the longitudinal axis of the rotatable latch element 58 to degree substantially equal to the pitch of the external thread 60 upon said actuator stem 52, so that there will be snug engagement of said latch edge in said external thread no matter to what position the actuator stem 52 may be rotated in the fitting 49. Stated otherwise, the actuator stem 52 includes a continuous external thread 60 adapted to snugly receive the latch edge 59 regardless of the position of rotatable adjustment of said actuator stem. Said latch edge 59 has length somewhat greater than a dimension representing the diameter of the actuator stem 52, and the construction and arrangement are such that both of the trunnions 57, 57 are in spaced relation to said actuator stem, at opposite sides thereof.

An actuating lever for the rotatable latch element 58 is represented by numeral 61. As disclosed, the actuating lever 61 is rigid with one of the trunnions 57 and extends away from the fitting 49 at right angular relation to the valve casing 28.

A time operated controlling means for the latching device is constituted as a clock mechanism 62, disclosed more clearly in Fig. 9. A pivoted arm 63 is urged toward the actuating lever 61 by a tension coil spring 64 and is retained stationary against the action of said tension coil spring by a cam 65 movable with the clock mechanism. The construction and arrangement will be such that the pivoted arm 63 will drop off of the cam 65 at the expiration of a set time and cause the actuating lever 61 to be tripped, thus to cause the latch element 58 to be rotated so that the latch edge 59 will be removed from the external thread 60 of the actuator stem 52.

In practical operation, the actuator stem 52 is first pushed down, both to cause the compression actuator spring 55 to be compressed between the collars 47 and 54 and the lower closure surface 40 of the double valve 39 to be engaged against the valve seat 31, and then the latch element 58 is rotated to cause the latch edge 59 to be engaged in the external thread 60 of the actuating stem 52. The compression coil spring 46 of course will have tendency toward moving the double valve 39 away from the valve seat 31, but the compression actuator spring 55, being of greater strength than said compression coil spring 46, will cause said double valve to be firmly engaged against said valve seat 31 under all conditions of use of the water softener. Upon release of the actuator stem 52 from the latch edge 59, the compression coil spring 46 will return the double valve 39 to its normal position of engagement against the valve seat 37. Said latch edge 59 will become removed from the external thread 60 upon said actuator stem 52 in response to but slight rotative movement of the latch element 58.

The salt tank 27 is adapted to receive solid salt 66, and a removable cover for said salt tank is denoted 67. The cover 67 when fastened down is water-tight. A screen 68 fixed in the lower portion of the salt tank includes ports 69, and the lower end of said screen is secured to a brine solution connecting pipe 70.

The pipe connection 17 includes a fitting 71 with valve, denoted generally at 72, for controlling flow of water from the inlet connection 15 and the pipe connection 16, by way of said pipe connection 17 and the pipe connection 17', to the container 18, a manually actuatable valve 13 for controlling flow of water from said inlet connection 15 and said pipe connection 16, by way of said pipe connection 17, to a water outlet 74 of the pipe connection 17, and a manually actuatable valve 75 for controlling flow of brine solution from the salt tank 27, by way of the connecting pipe 70, a brine solution inlet 76 of said pipe connection 17 and the pipe connection 17', to said container 18. A connecting pipe 77 for water is adapted to be detachably inserted between the water outlet 74 and a portion of the salt tank 27 above the level of the salt 66, and the brine solution connecting pipe 70 is adapted to be detachably connected with the inlet 76 of the pipe connection 17. The fitting 71 with valve 72 is situated at location between the pipe connection 16 and the pipe connection 17', the manually actuatable valve 13 is at the side of said pipe connection 16 opposite said fitting 71, and the manually actuatable valve 75 is at the side of said pipe connection 17' opposite the fitting 71.

An auxiliary drain pipe is represented 78.

The fitting 71 is constituted as a tubular member having a hollow inlet end portion 79 and a hollow outlet end portion 80 separated by a substantially Z-shaped partition extending across the tubular member and including a flat, intermediate portion 81 extending axially of said tubular member. A port 82 in the flat, intermediate portion 81, for affording communication between the hollow inlet end portion 79 and the hollow outlet end portion 80, is surrounded by a valve seat 83 at the inlet side of said flat, intermediate portion 81, and a valve proper 84 in said hollow inlet end portion 79 is adapted selectively to be engaged against and removed from the valve seat 83. Spaced apart guides 85 for the valve proper 84, perpendicular to and integral with the lower or inner surface of said valve proper, are slidably situated in the port 82 so as to project into the hollow outlet end portion 80. A restricted or reduced flow opening through said valve proper 84 is designated 86.

An actuator stem 87 for the valve proper, threadably situated in the fitting 71 in aligned and perpendicular relation to the valve proper 84, is rigid with a hand piece 88 at the outer side of said fitting 71 adapted selectively to be turned down to cause a foot 89 supported by said actuator stem within the hollow inlet end portion 79 to be engaged against the valve proper to cause it to be rested upon the valve seat 83 or turned up to withdraw said foot 89 from said valve proper thus to permit this to become removed from said valve seat 83. A compression coil spring 90, within the hollow outlet end portion 80 and confined by the spaced apart guides 85, is for normally urging the valve proper 84 away from the valve seat 83, toward the foot 89. As disclosed, one end of the compression coil spring 90 is engaged against the lower or inner surface of said valve proper 84 and the opposite end is engaged against an adjacent portion of the interior surface of the fitting 71.

When the water softener is operating between its periods of regeneration, the double valve 39 is positioned so that the upper closure surface 41 is engaged against the valve seat 37 to shut off communication between the outlet connec-

tion 20 and the drain pipe 36 and said outlet connection 20 is in free communication with the pipe connection 26 by way of the chamber 32 and the port 33. Said double valve 39 is retained positioned against said valve seat 37 by the compression coil spring 46. When the water softener is in water softening operation, the valves 21, 13 and 75 are closed and the valve proper 84 is in open position, up against the foot 89 as in Fig. 5 of the drawings. The flow of water from the inlet connection 15, through the pipe connections 16, 17 and 17', is downwardly through the zeolite bed and through the outlet connection 20 to the pipe connection 26 by way of the chamber 32 and the port 33 when the water softener is in softening operation.

When the softening medium or zeolite 22 is to be regenerated, the valve 72 is first closed, by manipulation of the actuator stem 87 to cause the foot 89 to be situated down against the valve proper 84 as disclosed in Fig. 3 of the drawings, the auxiliary drain pipe 78 is then removed from the drain pipe 36 and attached at 76 to the valve 75, and, finally, the valves 21 and 75 are opened. Thus, backwashing is caused to occur, the backwashing flow being from the inlet connection 15 through the pipe connection 26, the port 33 and the chamber 32 to the connection 20, and thence upwardly through the softening medium or zeolite 22, the pipe connections 17' and 17 and the auxiliary drain pipe 78 to drain.

Upon completion of backwashing, the valves 21 and 75 are closed, the drain pipe 78 is replaced on the drain pipe 36, and the salt tank 27, with solid salt therein, is connected up, by means of the pipe connections 17 and 70, to the valves 73 and 75, respectively. The valves 73 and 75 are then opened, and the double valve 39 is latched in the position as disclosed in Fig. 6 of the drawings, so that the pipe connection 26 is shut off from the pipe connection 20 and the drain pipe 36 is open to said pipe connection 20. Thus, water from the inlet connection 15 is caused to flow into the salt tank 27 by way of the pipe connections 16 and 17 and the water pipe 77, and brine solution is caused to be forced out of said salt tank into the container 18 by way of the pipe connections 70, 17 and 17'. The brine solution will be forced into said container 18 under head pressure of water in the inlet connection 15, and water and brine solution will flow downwardly through the container and out of the drain pipes 36 and 78, by way of the outlet connection 20, the chamber 32, the port 38 and the first hollow tubular element 34, with the forcing of water and brine solution from the salt tank 27 into said container 18. The brine solution thus made to flow into the zeolite container will cause the zeolite to be flushed and regenerated, and the valves 73 and 75 will be closed after flushing and regeneration of the zeolite is completed. The pipes 77 and 70 will be removed from said valves 73 and 75, respectively, while all of the valves 72, 73, 75 and 31-40 are closed.

After regeneration, it is necessary to wash the brine solution, and traces thereof, from the mineral bed. To accomplish this, and assuming the salt tank 27 and its connecting pipes 77 and 70 to have been disassociated or disassembled from the container 18, the timing mechanism is set on the latching device and the actuator stem 87 is moved to position, as in Fig. 4, adapted to permit the valve proper 84 to become removed from the valve seat 83 (while said latching device holds the valves 31-40 closed, and the valve 37-41

open and the valves 21, 73 and 75 are closed), thus to cause or permit water from the inlet connection 15 to flow downwardly through the zeolite bed 22, by way of the pipe connections 16, 17 and 17', and out of the drain pipes 36 and 78, by way of the outlet connection 20, the chamber 32 and the port 38. It is necessary that washing of the zeolite be continued for some appreciable time to insure that all traces of salt brine be removed, and, desirably, the flow of water through the zeolite bed to the accomplishment of the washing operation should be relatively slow thus to be thoroughly distributed throughout the zeolite bed. During washing, the valve proper 84 is in closed position, as in said Fig. 4, and flow of water is limited to that which passes the restricted or reduced flow opening 86 so that proper washing of the zeolite bed will be accomplished.

The construction and arrangement including the time controlled latching device before described is for retaining the valve 31-40 closed while the valve 37-41 is open and there is restricted flow through the reduced flow opening 86 for a predetermined sufficient interval of time which will cause washing of the zeolite to be complete and for automatically opening said valve 31-40 and closing said valve 37-41 upon the expiration of said predetermined sufficient interval of time. Opening the valve 31-40 and closing the valve 37-41 after washing of the zeolite is accomplished, causes the inlet connection 15, the pipe connections 16, 17 and 17', the zeolite container 18 and the outlet connection 20 to be open to the pipe connection 26, so that the water softener is set or ready to commence softening operation, and shuts off the drain pipe 36. The timing mechanism 62 of course will be set to cause the valve 31-40 to remain closed and the valve 37-41 to remain open for precisely the interval during which it is intended that washing of the zeolite bed be continued.

It will be apparent that during washing of the bed of zeolite, flow of water from the inlet connection 15 by way of the fitting 71 to and through the container 18 and out of the drain pipes 36 and 78 will be in the direction of the arrows in Figs. 3, 4 and 5 of the drawings. That is, flow through the fitting 71 will be from the hollow inlet end portion 79 to the hollow outlet end portion 80 of said fitting, and water under head pressure of water in the inlet connection 15 will cause the valve proper 84 to remain closed, engaged against the valve seat 83, as said valve proper is disclosed in Fig. 4, as long as the valve 37-41 remains open. When, however, the compression coil spring 46 causes the double valve 39 to be actuated to cause the outlet connection 20 to be shut off from drain and open to the pipe connection 26 leading to the locations of use, and thereafter pressure in the system becomes equal to head pressure in the inlet connection 15, the compression coil spring 90 will cause the valve proper 84 to be moved to wide open position, as said valve proper is disclosed in Fig. 5, thus to permit free flow through the water softener until regeneration again is accomplished. Attention is called to the fact that should a faucet on the line be open after regeneration is completed and before pressure in the system has equalized to permit the valve proper 84 to be opened, flow from the faucet will be at the rate permitted by the reduced flow opening 86.

The construction and arrangement of the fitting 71 and the valve 72 as illustrated and described constitute a valuable improvement over

the construction and arrangement as in the Kaysen Patent No. 2,329,350 where the restriction member 59 is at the outlet side of the two-way valve. In the disclosure of the application, there is no restriction at the outlet side of the two-way valve, and, hence, no built-up pressure operative against actuation of the double valve 39. In practical use of apparatus made according to the above identified Kaysen patent, it was necessary to slot the lower seat of the two-way valve to allow pressure to equalize on either side of said lower seat in the event a faucet of the system might be opened during washing or rinsing of the zeolite bed, and the slot established the possibility of passage of brine to locations of use. Placing the necessary restriction at the inlet side of the two-way valve, as in the application, effectually eliminates all of the difficulties which are encountered when the necessary restriction is situated at the outlet side of the two-way valve.

The purpose for the inclusion of the construction and arrangement for accomplishing washing of the zeolite bed for a predetermined sufficient interval of time and for causing the water softener to become automatically set or ready to be capable of commencing softening operation after washing is completed is to relieve the workman of the necessity of waiting around until washing of the zeolite bed has been accomplished. A workman need spend only a very few minutes to the accomplishment of the flushing operation of the softening medium or zeolite 22. The tank 27 for salt is readily and easily and quickly attachable to and detachable from the water softening medium or zeolite container 18, and, evidently, the construction and arrangement provide for really quick and thorough flushing of the zeolite with salt brine after the container 18 and the salt tank 27 are assembled together. The relatively short period of time required to assemble and disassemble the container and salt tank, to accomplish regeneration, and to set the timing mechanism, is all the time a workman need spend in order that regeneration and washing of the zeolite can be complete. The workman can be otherwise occupied during the much longer interval of time required for washing.

The salt tank and its connections will be removed from the softening medium container, as in Fig. 1, while the water softener is in softening operation.

What is claimed is:

1. In a water softener system, the combination with a container having a bed of softening medium, an inlet connection to said container and bed adapted to lead from a source of water supply, an outlet connection from said container and bed disposed in spaced relation to said inlet connection adapted to lead to locations of use for water, and a fitting in one of said connections including a port for affording communication between hollow inlet and outlet portions of said fitting, of a valve casing communicated with by said inlet connection by way of said hollow inlet and outlet portions of said fitting, said container and said outlet connection, a first pipe connection adapted to lead from said valve casing to said locations of use for water, a second pipe connection adapted to lead from said valve casing to drain, means adapted to be actuated selectively to shut off communication between said container with softening medium and said first pipe connection and establish communication by way of said outlet connection and valve casing between said container with softening medium and said

second pipe connection and to establish communication by way of said outlet connection and valve casing between said container with softening medium and said first pipe connection and shut off communication between said container with softening medium and said second pipe connection, mechanism for controlling said mentioned means, a valve in said fitting for controlling said port and including a reduced flow opening, resilient means for retaining said valve in the open condition of said port against the possibility of said valve becoming closed in response to flow of water through said fitting, and manually operable means selectively actuatable to a position adapted to cause said valve to be situated in the closed position of said port or to a position releasing said valve to render it capable of being situated in the open condition of said port, differential in pressure at the inlet and outlet sides of said fitting being adapted to retain said valve in the closed condition of the port against force of said resilient means when said manually operable means is actuated to said position releasing said valve to render it capable of being situated in the open condition of said port while said second pipe connection is open and there is differential in pressure between the source and outlet sides of said fitting, and said resilient means being adapted to urge said valve to the open condition of the port in response to closing of said second pipe connection and equalization in pressure at the source and outlet sides of said port.

2. The combination as specified in claim 1, a vessel for salt, a first connector between said inlet connection and said vessel, first manually actuatable means for selectively controlling flow of water from said inlet connection to said container or to said vessel by way of said first connector, a second connector between said vessel and said container, and second manually actuatable means for controlling flow of brine solution from said vessel to said container by way of said second connector.

3. In a water softening system, the combination with a container having a bed of softening medium, an inlet connection to said container and bed adapted to lead from a source of water supply, an outlet connection from said container and bed disposed in spaced relation to said inlet connection adapted to lead to locations of use for water, and a fitting in one of said connections including a port for affording communication between hollow inlet and outlet portions of said fitting, of a valve casing communicated with by said inlet connection by way of said hollow inlet and outlet portions of said fitting, said container and said outlet connection, a first pipe connection adapted to lead from said valve casing to said locations of use for water, a second pipe connection adapted to lead from said valve casing to drain, means adapted to be actuated selectively to shut off communication between said container with softening medium and said first pipe connection and establish communication by way of said outlet connection and valve casing between said container with softening medium and said second pipe connection and to establish communication by way of said outlet connection and valve casing between said container with softening medium and said first pipe connection and shut off communication between said container with softening medium and said second pipe connection, mechanism for controlling said mentioned

means, a valve in said fitting for controlling said port and including a reduced flow opening, resilient means for retaining said valve in the open condition of said port against the possibility of said valve becoming closed in response to flow of water through said fitting, and manually operable means selectively actuatable to a position adapted to cause said reduced flow opening to be closed and said valve to be situated in the closed condition of said port or to a position causing said reduced flow opening to be open and releasing said valve to render it capable of being situated in the open condition of said port, differential in pressure at the inlet and outlet sides of said fitting being adapted to retain said valve in the closed condition of the port against force of said resilient means when said manually operable means is actuated to said position causing said reduced flow opening to be open and releasing said valve to render it capable of being situated in the open condition of said port while said second pipe connection is open and there is differential in pressure between the source and outlet sides of said fitting, and said resilient means being adapted to urge said valve to the open condition of the port in response to closing of said second pipe connection and equalization of pressure at the source and outlet sides of said port.

4. The combination as specified in claim 3, a vessel for salt, a first connector between said inlet connection and said vessel, first manually actuatable means for selectively controlling flow of water from said inlet connection to said container or to said vessel by way of said first connector, a second connector independent of said valve casing between said vessel and container, and second manually actuatable means for controlling flow of brine solution from said vessel to said container by way of said second connector.
